Fig. 3.

Fig. 4.

FIGURE 1 is a perspective view of an electric motor base embodying my new design;

FIGURE 2 is a front view thereof;

FIGURE 3 is a top plan view thereof; and

FIGURE 4 is a side view thereof.

The design is characterized by a cradle-like portion which rises symmetrically from a rectangular base plate and has high end portions flanked by lower buttress-like side portions, and a depressed upwardly facing central portion.

I claim:

The design for an electric motor base, as shown and described.
